UNITED STATES PATENT OFFICE.

ALFRED STELL, OF STEETON, NEAR KEIGHLEY, AND JOHN STELL, OF KEIGHLEY, YORK, ENGLAND.

DOFFING APPARATUS FOR SPINNING, DOUBLING, TWISTING, AND LIKE MACHINES.

Application filed May 3, 1918. Serial No. 232,233.

To all whom it may concern:

Be it known that we, ALFRED STELL and JOHN STELL, subjects of the King of Great Britain, and residents, respectively, of Green 5 Hill, Steeton, near Keighley, in the county of York, England, and 34 Devonshire Street, Keighley, aforesaid, have invented a certain new and useful Improvement in Doffing Apparatus for Spinning, Doubling, Twisting, and like Machines, of which the following description, having reference to the accompanying sheets of drawings, is a specification.

Our invention relates to doffing apparatus 15 for machines known as cap spinning, doubling, twisting and like frames, and consists in an improved arrangement and construction of the several devices for performing the doffing operations whereby the number 20 of movements to be performed by the operative is less than with those of ordinary construction. These improvements consist particularly in a new arrangement and construction of receptacles for receiving full 25 bobbins and supplying empty bobbins to the spindles, as also in improvements relating to the "tin boards" or dividing plates which occupy positions between the spindles for purposes well known, these dividing 30 plates being automatically moved out of position on the lowering of the spindle rail or lifter plate during or prior to the performance of the doffing operations, while our improvements also comprise other improved details of construction forming our 35 complete doffing motion.

In order that our said invention may be readily understood, we have hereunto appended sheets of drawings illustrative thereof, to which, by figures and letters, reference is made in the following description.

Fig. 1 is an end elevation of a portion of a spinning machine having our improvements applied thereto, the different parts 45 being shown in the positions they occupy during spinning operations.

Fig. 2 is a front elevation of the parts shown by Fig. 1.

Fig. 3 is a sectional end elevation of a 50 portion of a spinning machine with our improvements applied and with the parts also shown in the positions they occupy during spinning.

Fig. 4 is a similar view to a portion of Fig. 3 and shows our apparatus as moved 55 during doffing operations.

Fig. 5 is a detail drawing illustrating the means for moving the dividing plates or tins as hereinafter described.

Fig. 6 is a plan showing two of the boxes 60 or receptacles above referred to mounted upon their supporting bar.

Fig. 7 is an elevation of one of said boxes or receptacles and as seen in the direction 65 indicated by the arrow w.

Fig. 8 is an end elevation of one of said receptacles.

Fig. 9 is a plan of our improved cap support or holder hereinafter described.

Fig. 10 is an end elevation thereof. 70

Fig. 11 is a detail of a modified form of the connection from the dividing plates to the lifter rail.

Figs. 6 to 10 inclusive are drawn to an enlarged scale as compared with the other 75 views.

Similar letters and figures of reference indicate like parts throughout the several views.

A, A¹ represent the top and bottom cross 80 rails of the machine and B the spindle rail, which latter is capable of being raised and lowered in the ordinary manner by means of the racks a and pinions a¹ operated from the hand wheel a² through the gear wheels a³, a⁴. The spindles 1 carry caps 2 and the lifter plate 3 is reciprocated in the common and well known manner, the usual devices also being arranged in connection therewith whereby when doffing operations are to be 90 performed the device for reciprocating said lifter plate mechanically may be put out of gear and said lifter plate operated by hand.

Mounted in appropriate bearings as those 95 b¹ is a shaft b upon which are mounted gear wheels b² which gear with racks b³ while said shaft b has fixed upon it a hand lever or the like b⁴ by which the shaft b is oscillated and the racks b³ raised into the position indicated by Fig. 4 or lowered therefrom into the positions indicated by Figs. 100 1 and 2. These racks b³ carry other bearings c within which reciprocate racks c¹ pinions c² mounted upon the shaft c⁴ gearing with said racks c¹, an appropriate handle as c³ being mounted on the shaft c⁴ by which

the racks c^1 may be moved towards or away from the framework C. The said racks c^2 have fixed upon them a plate d extending the length of the frame such plate d having fixed upon it at desired intervals brackets d^1 which carry a bar d^2 also extending the length of the machine. Mounted upon the bar d^2 are a series of boxes or receptacles e these also extending throughout the whole 10 length of the frame. They have attached to them brackets e^1 which slide upon the bar d , and they are capable of being moved simultaneously lengthwise the machine by means of the handle f fulcrumed at f^1 and engaging with projecting parts or ears e^2 formed or mounted upon the brackets e^1 . These boxes or receptacles are for the reception of full bobbins x and empty bobbins y , the said empty bobbins y being supplied 15 to these receptacles by the operative during spinning operations when such receptacles occupy the positions indicated by Fig. 2, wherein the bobbins y are approximately midway between the series of spindles 1.

20 One portion e^3 of each receptacle is in the form of a vertically disposed tube and is for the reception of an empty bobbin, an opening or slot e^4 being made in the base and sides of said receptacles in order that same may be passed laterally over the spindles 25 for the purposes hereinafter described. The lower flange of the empty bobbin y is supported by the part e^5 of the base of the receptacle. These receptacles, as shown by 30 Figs. 6, 7 and 8, fit closely against each other the space intervening between one vertically disposed tube e^3 and the next forming a chamber or holder for the reception of a full bobbin x somewhat as shown in broken 35 lines by Fig. 6. A part e^4 is cut out of the end of each receptacle as shown by said Fig. 6 and the straight or regular end or surface of the neighbouring receptacle e extends alongside said slotted part to form the slot 40 e^4 for the purpose referred to.

Extending lengthwise the frame is a shaft h preferably square in cross section such shaft having mounted upon it a number of 45 depending arms h^1 provided with extending parts or shoes h^2 these being for the purpose of supporting the full bobbins in the manner hereinafter described. Normally these parts h^1 occupy positions approximately mid-way between the series of spindles 1. During doffing operations the shaft h may be moved longitudinally by its operating handle h^3 to bring said shoes opposite to said spindles and beneath the flanges of the full bobbins x . The operating handle 50 h^3 is provided with an extending pin h^4 which takes through openings in the end frame of the machine or in the bracket h^5 , and when said pin h^4 is in one position in

said end frame the arms h^1 and shoes h^2 are in the positions illustrated by Fig. 3. However when doffing operations are to be performed the shaft h is moved horizontally by the handle h^3 and immediately the pin h^4 is clear of the opening through which it takes the shoes h^2 are then in position opposite to or in alignment with the spindles 1.

Taking through appropriate bearings m^1 are a series of racks m operated by quadrants m^2 fixed upon a shaft m^3 at the end of which is a lever arm m^4 having a handle m^5 by which it is moved. These racks m carry a plate or bar n extending lengthwise the machine and having mounted upon it plates n^1 having slots n^2 of sufficient width to pass over the necks 2^a of the caps 2 but sufficiently narrow for the heads 2^b of said caps 2 to rest thereon. The bar n is capable of being moved from the position indicated by Fig. 3 to a position where when the caps are raised as hereinafter described the plate will pass over the necks 2^a and support the heads 2^b , while they are provided with short upwardly extending lips n^4 for the purpose of preventing the heads 2^b of the caps 2 from being easily dislodged from said holders n^1 . The movement of said plate n is effected by said handle m^4 which is moved from the position indicated by Fig. 1 wherein it engages with a notch in the quadrant plate m^6 to the position wherein said lever engages with the notch m^7 in said plate m^6 thus the operative may easily tell when the correct amount of movement has been given to said plates m^1 .

Also carried by the plate n by means of brackets o is a plate o^1 extending lengthwise the machine and to this plate o^1 are hinged at o^2 the tread guide boards o^3 and dividing plates s , thus when said plate n is moved away from the top rail A it carries with it the parts n^1 , the boards o^3 and the dividing plates or tins s , while when said tins s are automatically moved as hereinafter described they carry with them the said boards o^3 . Fixed upon the part s^1 carrying the dividing plates s is a lever t which has a chain connection t^2 extending to a bracket t^1 fixed upon the spindle rail B. Normally, that is when the parts are in the spinning position, the chain connection t^2 is somewhat slack, however when the spindle rail is lowered as during doffing operations this chain t^2 becomes tight or taut and lowers said lever t thus swinging the parts s and o^3 upon their hinge o^2 moving them from the position indicated by Fig. 3 into that shown by Fig. 4 wherein the plates s are moved entirely away from the caps 2 and spindles 1. On the rising of the spindle rail these parts either by gravity or as

sisted by counter-balancing weights or springs return to their normal positions. Instead of moving the dividing plates *s* upwardly as above described, we may so arrange the connections to the spindle rail *B* that said plates *s* are lowered or swung upon their fulcrum, and in order to allow those plates which are opposite to the framework or "bearers" to move as desired we 10 form them in sections or in the nature of a fan by which they may collapse or fold when lowered and assume their normal positions as they are raised. Further than this, we may arrange the connections from the plates 15 *s* to the lifter plate *3* instead of to the spindle rail *B*, the said plates *s* being moved thereby as hereinbefore described. The connection *b*² is slack enough to allow the necessary reciprocations of the lifter plate *3* 20 during spinning operations, while on the further lowering of said plate *3* during doffing operations said connection *t*² moves said plates *s* as desired.

The usual rod *v* for causing the severing 25 or breaking of the threads is carried by lever arms *v*¹, these being supported by the rod *v*² carried by brackets *v*³ mounted upon the plate *d*.

The actions of our improved apparatus 30 are as follows:—

Taking it that the full bobbins *x* have received their complement of yarn and it is desired to doff or remove same from their spindles and substitute therefor a series of 35 empty bobbins *y*, the handle *h*³ is moved so as to withdraw the pin *h*⁴ from its opening and carry the shoes *h*² opposite to the spindles 1 and by releasing said handle *h*² these shoes are allowed to move by gravity 40 towards said spindles 1. The spindle rail *B* is then raised by means of the hand wheel *a*² to a position wherein the plates *n*¹ are opposite the necks *2*^a of the caps 2 this position of the spindle rail being determined by 45 same coming into contact with an appropriate fixture on the framing *C* of the frame. The bar *n* is then advanced by the quadrants *m* to support the caps 2 in manner hereinbefore described, after which the lifter plate *3* is raised to such a position 50 that the shoes *h*² occupy positions between the lower ends of the full bobbins *x* and the upper ends of the wharles 4 on which the shoes *h*² are passed beneath the bobbins' flanges, where they are held by the pin *h*⁴ taking into another opening in the 55 framework *C* formed in the proper position for this purpose. The lifter plate *3* is then lowered by hand to approximately the position indicated by Fig. 4, and the spindle rail also lowered until the upper ends of the spindles 1 are slightly below the lower ends of the caps 2, the full bobbins *x* being sup-

ported by the shoes *h*² in the manner indicated in broken lines by said Fig. 4. After 65 these operations the plate *n* is returned so as to carry the caps 2 into position in proximity to the beam or rail *A* on which the racks *c*¹ are advanced by their pinions *c*² to pass the receptacles *e* laterally over the spindles 1 and beneath the full bobbins *x* after 70 which the receptacles *e* and other parts carried by the plate *d* are raised by the rack *b*² and wheel *b*³ carrying the full bobbins upwardly until the lower ends of said full bobbins are above the upper ends of the spindles 1 on which the receptacles *e* are moved by the lever *f* so as to bring the empty bobbins opposite to and vertically above the spindles 1. The racks *b*³ are then lowered 75 passing the empty bobbins *y* over the spindles 1, this movement being continued until the receptacles *e* are below the lower ends of said empty bobbins *y* on which said receptacles are withdrawn by the rotation of the pinions *c*². The shaft *h* is then oscillated to allow the empty bobbins to fall upon the upper ends of the wharles 4 and the rail *n* again advanced to cause the caps 2 to 80 occupy positions vertically over the spindles 1. The spindle rail *B* is raised sufficiently for the spindles 1 to support said caps 2 after which said rail *n* is returned in proximity to the bar or beam *A*. The spindle rail *B* is then lowered to the spinning 85 position and the lifter *3* raised. The full bobbins are moved back to their positions opposite to the spindles 1 and the rod *y* turned over so as to rest upon the threads extending to said full bobbins, so as to sever them on the rotation of the empty bobbins *y*. 90

During the descending of the lifter rail *B* the dividing plates or tins *s* will be raised into the position shown by Fig. 4 and returned to their normal positions on the raising of said rail *B* in the manner hereinbefore described.

Such being the nature and object of our said invention, what we claim is:—

1. In spinning, doubling, twisting and like machines, a series of spindles, a rail carrying said spindles, means for raising and lowering said rail, a series of dividing plates or tins, supports for said plates or tins, and a chain and lever connection between said supports and said spindle rail whereby movement of the latter causes oscillation of the dividing plates or tins.

2. In spinning, doubling, twisting and like machines, a series of spindles, supports for said spindles, a series of bobbins fitting over said spindles, lifter plate for supporting and traversing said bobbins, a series of dividing plates or tins, means for supporting same, means for traversing said supports horizontally, and a chain connection

between said supports and said lifter plate whereby vertical movement of the latter causes oscillation of said plates or tins.

3. In spinning, doubling, twisting and like machines, a series of spindles, a series of receptacles, means for raising and lowering said receptacles, means for moving said receptacles horizontally in directions at right angles to each other, a series of caps

mounted on said spindles, supports for said caps, a bar carrying said supports and the supports for a series of dividing plates or tins and thread guide boards, and means for operating said bar horizontally to move said plates or tins, cap holders simultaneously.

ALFRED STELL.
JOHN STELL.
